UNITED STATES PATENT OFFICE.

MARSHALL PARKS AND VIRGINIUS FREEMAN, OF NORFOLK, VIRGINIA.

DREDGING-MACHINE.

SPECIFICATION forming part of Letters Patent No. 244,480, dated July 19, 1881.

Application filed May 17, 1881. (No model.)

To all whom it may concern:

Be it known that we, MARSHALL PARKS and VIRGINIUS FREEMAN, of Norfolk, in the State of Virginia, have invented certain new and useful Improvements in Dredging-Machines, of which the following is a specification.

The machine in which our improvements are embodied can be employed as a dipper or grapple dredge, and may be used either on a barge or on land for excavating purposes.

It is our object to obtain a wide range of movement for the boom, so as to permit it to be turned to different quarters of the compass, and thus brought opposite to various points where work is to be done without moving the whole machine. With this in view we mount the boom and the engine and operating mechanism upon a revolving or semi-revolving table or platform, and so arrange the steam-supply connection between the engine and the boiler (which is not mounted on and does not move with the platform) that the platform may be moved to any required extent within the limits of its range of movement without interfering with continuous steam-supply. We also combine with the platform and boom improved instrumentalities in the nature of brakes, which check the movement of these parts at any desired point.

The nature of our improvement and the manner in which the same is or may be carried into effect can, however, best be explained and understood by reference to the accompanying drawings, in which—

Figure 1 is a plan, Fig. 2 is a sectional side elevation, and Fig. 3 is a like end elevation, of a steam dredging-machine embodying our improvements. Fig. 7 is a sectional side elevation, on an enlarged scale, of that portion of the machine particularly embodying our invention. Fig. 8 is an end elevation of the front end of the boom and the dipper-handle carried by the same. Figs. 4, 5, 6 are views of a detail hereinafter referred to.

A is the barge which carries the machine. Upon a suitable bed, B, erected on the barge, rests the revolving circular table C, which is secured to a central hollow cast-iron cylindrical sleeve, D, which fits and is adapted to revolve within a corresponding sleeve, E, fixed to the bed B. The table is supported near its pe-

riphery by cast-iron wheels *a*, which are mounted on wrought-iron arms or axles *b*, radiating from the cylinder or sleeve D, and the two cylinders D E, in order to afford proper support to the table at its center, are provided with horizontal flanges D' E', which, on their contiguous faces, are recessed, as shown, to receive a number of conical or spherical rollers, *d*, (movable in the recess,) on which the table bears.

Attached to the revolving sleeve D is a boss or projection, *e*, to which is pivoted or hinged at *e'* the boom F, within or upon which boom the dipper or grapple handles work in the usual way, as indicated at F'. The boom is supported by stays *f*, of iron chain or wire rope, which lead from the boom to a wrought-iron band, *g*, mounted so as to be capable of rotating on a cast-iron cap, *h*, which surmounts the converging upper ends of the four posts or struts *G*, whose lower ends are firmly secured to the barge.

The engine (shown at H) is of any ordinary or usual type, and is connected with the usual mechanism for working the dipper or grapple. It is placed on the revolving table C and moves therewith. The steam-boiler I, however, is not carried by the table, but is stationary, being placed in the barge below the table, as shown.

In order to supply steam from the boiler to the engine, we provide a steam-pipe, *i*, which passes vertically and axially up through the hollow revolving sleeve D, and has at *i'* a slip, ball, or other packed joint, which permits the upper section of the steam-pipe to revolve in the lower section. It also has at the point *i''* another slip-joint, which will permit limited endwise and other requisite movements of the steam-pipe sections which there meet, in order that they may accommodate themselves to oscillations or irregular movements of the revolving table. By this arrangement we obtain capacity for free movement of the table without interfering with continuous steam-supply.

The engine also is used to furnish the power by which the table is revolved. To this end there is mounted in the table a vertical rotary shaft, *j*, which, by suitable gearing, is driven by the engine. On the lower end of this shaft is a pinion, *k*, which meshes with a semicircu-

lar rack, *l*, fixed to the outer vertical wall of an annular recess, *B'*, formed in the bed *B*. By means of a clutch or other suitable device the shaft *j* is thrown into gear with the engine 5 whenever it is desired to shift the position of the table.

In order to neutralize the tendency of the boom to tilt the table, we arrange on the edge of the table (on the side opposite that where 10 the boom is) a series of friction-rollers, *m*, which run under the horizontal ledge of a semicircular retaining-bracket, *n*, fastened to the bed *B*.

The table, being heavily weighted, necessarily has, when it is once in motion, considerable 15 momentum. It becomes necessary, therefore, to provide means whereby its movement can be arrested with certainty, and without undue strain upon the parts. To this end we make use of a double friction-brake. (Shown plainly 20 in Fig. 2.)

J is the lever by which the double brake is operated. It is pivoted at *o* to the table, down through which its lower end extends. To this lower end are jointed two horizontal sliding 25 rods, *p p'*, supported one above the other in hanger-bearings *p²*, which will permit them the necessary freedom of movement, and carrying at their outer ends brake-shoes *p³*. The brake-shoe of the lower rod, *p'*, bears against 30 the outer wall of the recess *B'* in the bed, and the brake-shoe of the upper rod bears against a semicircular abutment, *p⁴*, which partly encircles the table, and is erected upon the bed *B*. By moving the lever in the proper direction 35 both brake-shoes will be applied simultaneously. By this arrangement, even if one brake-shoe should happen to be out of order, the other would be operative. Moreover, the application of the brake-shoes in the manner 40 specified enables the engineer to control with great certainty and accuracy the movements of the table.

In order to provide a still further means which may be used to arrest movement of the 45 table in case the brake just above described should for any reason happen to be inoperative, and which can also be employed, whenever desired, to neutralize the tendency of the boom to continue to swing or move independently of the table, we make use of an iron-chain or wire-rope stay-brace, and clamp therefor, which are shown more particularly in Figs. 4, 5, 6, Fig. 4 being a rear elevation of that portion of the framing which carries the clamp 50 and conical spools, together with a portion of the boom, Fig. 5 a plan of the same, and Fig. 6 a side elevation of the clamp.

The stay-brace is shown at *r*. It is secured at the points *r' r'* to the boom, and thence 55 passes around spools *s*, (which, preferably, are conical,) and between sheaves *t*. Under this arrangement it will be seen that the brace can adapt itself without difficulty to various positions to which the boom may be brought by 60 the revolving table so long as the brace is free to move between the sheaves. Should, how-

ever, the sheaves be drawn tightly together, so as to close on the brace, the latter would then be prevented from further motion and would check further movement of the boom. 70

To arrange the sheaves so that they may have this function, we mount them in a suitable metallic frame, *v*, attached to a cross-piece, *v'*, extending between the two side struts *G*. The lower sheave has a stiff spring-supported bearing, as indicated, the object of which is to hold up the sheave toward the other far enough to keep the brace-chain in the bite of the sheaves and yet permit them to move to and from one another to accommodate themselves to the irregularities of the chain. The upper sheave is mounted on bearings which can slide up and down, and are connected by a yoke-like strap, *w*, to a lever, *x*, pivoted at *x'* to the cross-piece *v'*, and provided with a pin, *x²*, which enters a hole or slot in the lower end of strap *w*, as seen in Fig. 4. To lever *x* is jointed a handle, *y*, which hangs down in convenient proximity to the engineer. Whenever, for any reason, this mechanism is to be put in action the engineer 80 pulls down on the handle *y*, which has the effect of drawing together the two sheaves, clamping them upon the brace between them with such force as to check and speedily arrest further movement of the brace and boom with 85 which it connected. 90

The spools *s* are made conical, in order to take up slack, which occurs as the boom is moved by the table to one position and another. 100

Having described our improvements, what we claim, and desire to secure by Letters Patent, is—

1. The combination of the revolving-table, the engine, boom, dipper or grapple, and operating mechanism mounted on and moving with the table, the stationary boiler, and the steam-pipe extending from the boiler to the engine axially through the table and table-bearings, and provided at that point with a joint 105 which permits the one pipe-section to revolve in or on the other, substantially as and for the purposes hereinbefore set forth.

2. The bed and hollow-bearing cylinder fixed therein, in combination with the table, the 110 mechanism carried by the same, and the cylindrical sleeve fixed to and moving with the table and fitting into the fixed bed cylinder, and the steam-pipe extending up through said sleeve to the engine. 120

3. In combination with the bed and the revolving table and mechanism carried by the same, the brake-lever and double brake constructed and arranged for operation as and for the purposes herein shown and set forth. 125

4. The stay-brace and clamping mechanism, in combination with the fixed struts or supports, the spools, the revolving table, and the boom, substantially as and for the purposes set forth. 130

5. The combination, substantially as hereinbefore set forth, of the fixed struts or supports,

the bed, the revolving table, and the boom, the double brake, the stay-brace, and the brace-clamp.

6. In combination with the revolving table, the engine carried thereby, and the stationary boiler, the steam-pipe passing from the boiler axially through the table to the engine, and composed of sections jointed together at two points, substantially as described, so that they may move with respect to one another to ac-

commodate themselves to the varying movements of the table, substantially as hereinbefore set forth.

In testimony whereof we have hereunto set our hands this 16th day of April, 1881.

MARSHALL PARKS.
VIRGINIUS FREEMAN.
